DRY CLEANING SOLVENT

Alfred Hirsch, Mentor, Francis Huba, Painesville, and Roland J. Horvath, South Euclid, Ohio, assignors to Diamond Alkali Company, Cleveland, Ohio, a corporation of Delaware

No Drawing. Filed Aug. 7, 1964, Ser. No. 388,277

6 Claims. (Cl. 252—171)

This invention relates to halogenated solvents, and more particularly to improved solvent compositions suitable for use in the dry cleaning and specialty cleaning arts, and characterized by selective solvent action, good thermal stability, convenient boiling point range, and low flammability and toxicity.

Because of their wide use in large quantities by persons of relatively little training in the handling of toxic or dangerous chemicals, cleaning solvents must be relatively safe to use. They must also have selective solvent action so that they will dissolve and wash away undesirable dirt and grease without dissolving portions of the goods being cleaned. Moreover, the solvents should have a low degree of flammability and a boiling point which is high enough to avoid excessive loss at dry cleaning temperatures and yet low enough to permit easy removal of the solvent from the goods after cleaning.

The substances currently in widest use as solvents for cleaning both fabrics and special items such as electronic components and magnetic tapes are chlorinated solvents such as trichloroethylene, perchloroethylene and methylchloroform. Their major disadvantages include boiling points too high for convenient use and the property of dissolving certain plastics used, for example, in buttons and ornamentation on clothing and also in certain types of electrical mountings, insulations and color codings. Perchloroethylene has the additional disadvantage of being toxic enough to require rather careful handling.

Another common cleaning solvent, carbon tetrachloride, is so toxic as to create a serious health hazard, especially when used in large quantities. Stoddard solvent, a high boiling petroleum naphtha fraction, is quite flammable and is also hard to remove after the cleaning process because of its low vapor pressure. 1,1,2-trichloro-1,2,2-trifluoroethane, a dry cleaning solvent recently described in U.S. Patent 3,042,479, is too expensive for wide use, has limited solvent power and is also extremely volatile (boiling point 46° C.) so that solvent losses are a serious problem in normal cleaning processes. Indeed, it is often necessary to refrigerate the solvent for recovery.

A principal object of the present invention, therefore, is to provide new solvents which are useful for cleaning a wide variety of items and substances.

A further object is to provide compositions with selective solvent action, thermal stability and non-flammability and favorable physical properties for cleaning solvent applications.

A further object is to provide solvents which have low toxicity.

Still another object is to provide a solvent which may be used in a number of cleaning applications including dry cleaning, cold cleaning, ultrasonic cleaning, vapor degreasing and the like.

Other objects and advantages of the present invention will in part be obvious and will in part appear hereinafter.

2

The present invention comprises a composition of matter suitable for use as a cleaning solvent which contains a major proportion of at least one tetrachlorodifluoroethane. More specifically, it comprises a solvent consisting essentially of a substantially constant-boiling mixture of major proportion (about 70–85% by weight) of tetrachlorodifluoroethane and a minor proportion (about 15–30% by weight) of at least one diluent therefor, said diluent being a halogenated hydrocarbon which is normally a liquid at room temperature.

5 Tetrachlorodifluoroethane ($C_2Cl_4F_2$) exists in two isomeric forms, symmetrical and unsymmetrical, melting at 23.8° C. and 40.6° C., respectively. Both isomers boil at about 92° C. A mixture of these two compounds is 10 commercially available and has a melting point of 30.6° C. It has been found that tetrachlorodifluoroethane has excellent solvent properties for dry cleaning purposes; however, its high melting point precludes its use in pure form. According to this invention, therefore, the melting point of tetrachlorodifluoroethane is depressed by the addition of about 15–30%, preferably about 20–25%, by weight of a liquid halogenated hydrocarbon diluent.

15 In commercial use, it is important that the composition of a dry cleaning solvent remain constant or nearly constant even after repeated cleaning cycles. When the solvent is a single compound, this presents no problem. But when a mixture of compounds is used, there may be a 20 change in composition as it is used unless the components are chosen carefully with an eye toward behavior on distillation or vaporization. A material of essentially constant composition may be obtained by choosing an azeotropic mixture or by using components whose boiling points are so close that separation under the conditions of use does not occur. For the purpose of this invention, two 25 compounds have been found particularly useful and are preferred diluents for depressing the melting point of tetrachlorodifluoroethane; they are trichloroethylene (B.P. 87° C.) and 1,1,2-trichloro-1-fluoroethane (B.P. 88° C.).

30 1,1,2-trichloro-1-fluoroethane may be prepared by either 35 of two methods. The first and preferred method is by the reaction of trichloroethylene with hydrogen fluoride in the presence of a Lewis acid catalyst (e.g., boron trifluoride), as described in British Patent 684,117. This method gives the desired product in about 80% yield; because of 40 the closeness of the boiling points of starting material and product, the reaction mixture may be subsequently chlorinated to convert unreacted trichloroethylene to penta-45 chloroethane before the product is separated by distillation. Alternatively, since either the reactant or the product 50 may be used as diluents, separation thereof may be eliminated and the mixture used directly.

An alternative method for the synthesis of 1,1,2-trichloro-1-fluoroethane is by the reaction of 1,1,1,2-tetra-55 chloroethane with hydrogen fluoride in the presence of an antimony fluoride catalyst.

As indicated hereinabove, the preferred composition of the solvent of this invention is about 75–80% (by weight) tetrachlorodifluoroethane and about 20–25% trichloroethylene or 1,1,2-trichloro-1-fluoroethane. Solvents with 60 this composition have melting points in the range of about –30° to –20° C., and boiling points of about 88° C.

The compositions of this invention have a combination of properties which make them excellent for use as dry cleaning solvents. They are substantially less toxic than

perchloroethylene. Their vapor pressure is high enough so that they can easily be removed from fabrics at moderate temperatures, leaving little or no odor. They are stable over long storage periods and at temperatures as high as 200° C. (392° F.). They are non-flammable and non-corrosive, and are compatible with a wide variety of emulsifiers and dry cleaning soaps. The emulsifiers may be present in quantities up to 2% by weight. The following are exemplary of emulsifiers in current use.

10 Non-ionic:

Ethylene oxide condensation products of phenols and high molecular weight aliphatic alcohols,

Phosphate esters of the above,

Sorbitan monooleate-fatty acid ester combinations,

Cationic:

Cyclic tertiary amines,

Tetrakis(2-hydroxypropyl)ethylenediamine esters of high molecular weight carboxylic acids, quaternized with dimethyl sulfate,

Anionic: Alkali metal and amine salts of petroleum sulfonates, alkyl aryl sulfonates, ether sulfonates, carboxylic-sulfonic acid esters, etc.

The solvent compositions of this invention are also useful for cleaning metal stampings, magnetic tapes, printed circuits, vacuum tube parts, and electronic components such as switches, relays, potentiometers and resistors, since, in addition to the advantageous properties described

4 Table I

	Solvent A	Solvent B	Perchloroethylene
5 Color-----	(1) 87-88	(1) 88-89	(1) 121

¹ Colorless.

Toxicity measurements show that Solvent A is about one-half and Solvent B about one-fifth as toxic as perchloroethylene.

Other physical properties which are important to the action of a dry cleaning and specialty solvent include evaporation rate, solvent power (kauri-butanol number and mixed aniline point) and surface tension. These properties are determined by standard methods established by the American Society for Testing Materials. The evaporation rate is based on a figure of 100 for carbon tetrachloride. The kauri-butanol number is an empirical figure which increases with increasing solvent power. The mixed aniline point is the temperature at which a standard solute dissolves and therefore decreases with increasing solvent power. Surface tension is determined by means of the capillary rise method. These properties are given for several solvents in Table II.

Table II

Solvent	Evaporation Rate	Solvent Power		Surface Tension, dynes/cm. (20° C.)
		Kauri-Butanol Number	Mixed Aniline Point °C.	
Solvent A-----	67	85	25.8	24.0
Solvent B-----	69	93	23.2	24.8

hereinabove, they have a selective solvent action whereby they readily remove soldering flux, dirt, and other undesirable materials but do not attack plastic or fabric insulating materials and color codings, on resistors and the like. Further, they are relatively poor solvents for lubricant materials used on potentiometers and the like; this is an advantage because it is desirable that such lubricant materials remain on the parts through the cleaning process.

In the following description and examples, two specific solvent compositions are representative of the compositions of this invention. All percentages are by weight unless otherwise indicated.

Solvent A contains 80% $C_2Cl_4F_2$ and 20%

Solvent B contains 75% $C_2Cl_4F_2$ and 25%

Table I gives various physical properties of Solvent A, Solvent B and perchloroethylene.

55 It will be seen from Table II that Solvents A and B have intermediate evaporation rates, high enough for easy removal from the substances being cleaned but low enough to eliminate high solvent losses. Solvent powers of the solvents of this invention are intermediate between the aliphatic hydrocarbons and various powerful chlorinated hydrocarbon solvents.

60 Low surface tension is important in a cleaning solvent in order that the solvent may easily penetrate into inaccessible areas and beneath dirt and other materials to be removed. Table II shows that the surface tensions of Solvents A and B are relatively low as compared with other solvents normally used for cleaning.

The invention is illustrated by the following examples.

EXAMPLE 1.—PREPARATION OF 1,1,2-TRI-CHLORO-1-FLUOROETHANE

A one-gallon stainless steel autoclave is charged with 2630 g. (20 moles) of trichloroethylene and 26.3 grams of boron trifluoride (in the form of a methanol solution). The autoclave is sealed and 800 g. (40 moles) of hydrogen fluoride is introduced. The system is heated to 150° C.

and maintained at that temperature with stirring for about two hours; the internal pressure is about 600 psi.

The autoclave is then cooled and vented; the unreacted hydrogen fluoride is absorbed in ice water. The product liquid (shown by vapor phase chromatographic analysis to be 78.4% 1,1,2-trichloro-1-fluoroethane, 19% trichloroethylene and 2.6% 1,2-dichloro-1,1-difluoroethane) is

5

EXAMPLE 3

The compatibility of three solvents with common emulsifying agents used in dry cleaning is tested by measuring the solubility of water in a solution of 1-2% by volume of the emulsifier in the solvent. All listed emulsifiers are anionic with the exception of Kleerwite 200, which is non-ionic. Results are given below.

Emulsifier (Percent by volume)	Water Solubility (Percent by weight)								
	Solvent A			Solvent B			Perchloroethylene		
	0	1	2	0	1	2	0	1	2
None.	0.011			0.017			0.006		
Perclite (Signal Chemical Co.)	0.11	0.23		0.14	0.20		0.74	1.26	
Power Pack (Pennsalt Chemical Corp.)	0.03	0.04		0.04	0.04		0.03	0.03	
Buckeye 250 (Davis Young Soap Co.)	1.05	1.05		0.08	1.10		0.02	0.03	
Code 166 (Davis Young Soap Co.)	0.07	0.11		0.07	0.11		0.06	0.06	
Fortified Power Pack (Pennsalt Chemicals Corp.)	0.01	0.07		0.02	0.06		0.01	0.04	
Kleerwite 200 (Marcelene Chemical Co.)	0.20	1.74		0.19	0.86		0.13	0.78	
Pace Perk (Caled Products)	0.26	0.95		0.43	2.08		0.24	0.93	

¹ Cloudy.

washed with ice water, dried over calcium chloride and distilled.

To the product is added a small amount of anhydrous ferric chloride, and chlorine is passed through at 46-62° C., in the dark, until vapor phase chromatographic analysis shows the absence of trichloroethylene. The mixture is washed free of chlorine and hydrogen chloride with water, dried and distilled through a 20-inch packed column at a reflux ratio of 1:1. The product, 1,1,2-trichloro-1-fluoroethane, is collected at 88° C. at atmospheric pressure.

30

From the above it will be seen that the compatibility of the solvents of this invention with common dry cleaning emulsifiers is comparable to that of perchloroethylene.

EXAMPLE 4

Corrosion studies are run on a number of metal and plastic-coated metal strips by allowing a stream of moist air containing 10% by volume of solvent to pass over the strips for fourteen hours at 120° and 200° C. Results are given below, in terms of corrosion in mils per year.

Test Strip	120° C.			200° C.		
	Solvent A	Solvent B	Perchloroethylene	Solvent A	Solvent B	Perchloroethylene
Chrome plated steel	0.09	0.12	0.61	0.51	0.44	0.56
Nickel plated steel	0.35	0.36	0.65	0.48	0.39	0.41
Tin plated steel	0.94	0.85	1.59	5.08	4.84	3.78
Copper	1.47	3.34	1.47	3.28	7.29	32.78
Brass	0.92	2.17	0.98	3.24	3.73	3.18
Zinc	0.03	4.96	1.44	0.91	0.30	0.42
Aluminum	2.52	1.59	2.62	5.74	2.64	4.42
Shim steel	0.30	0.94	1.15	1.58	1.28	0.89
Galvanized	2.87	1.74	0.60	5.01	6.53	4.39
Rubber	(¹)	(¹)	(¹)			
Vinyl coat on aluminum	(¹)	(¹)	(²)	(³)	(⁴)	(³)
Acrylic coat on aluminum	(³)	(⁵)	(³)	(³)	(⁶)	(²)
Polyvinyl fluoride coat on aluminum	(²)	(²)	(²)	(²)	(²)	(³)

¹ Darkened.

² No change.

³ Partially dissolved.

⁴ Turned tan.

⁵ Turned pink.

⁶ SI. darkened.

EXAMPLE 2

Comparative laboratory tests are run on the ability of three solvents to remove oily materials from wool; results are given below. (Lanolin is an ingredient in many cosmetics; cetyl alcohol is present in lipsticks; and oxidized trioleum is a typical degradation product formed when skin secretions remain in prolonged contact with clothing.)

60

	Percent of soil removed		Perchloroethylene
	Solvent A	Solvent B	
Lanolin	99	96	98
Cetyl alcohol	98	99	99
Oxidized trioleum	97	99	95

From these results, it will be apparent that both Solvent A and Solvent B are equally as effective or more effective than perchloroethylene.

65

The effect of the solvents of this invention and of perchloroethylene on plastics used to make buttons, belt buckles and other textile ornamentation is tested by placing a weighed sample of the plastic in a vial of solvent and agitating at 24° C. for one hour on a shaker machine.

The solvent is then drained and the sample is dried for one hour at a pressure of 10 mm. of mercury and weighed. Percent weight change and visual appearance are tabulated below for the following samples.

1—Styrene-butadiene-acrylonitrile copolymer, molding grade.

2—Same, extrusion grade.

3—Melamine resin.

4, 5—Cellulose acetate butyrate.

6—Cellulose acetate.

7—Acrylate molding powder.

75

EXAMPLE 5

Sample No.	Solvent A		Solvent B		Perchloroethylene	
	Percent wt. change	Physical appearance	Percent wt. change	Physical appearance	Percent wt. change	Physical appearance
1	-1.07	0	+0.15	0	-0.09	0
2	+0.13	1	+0.53	2	+1.49	1
3	-0.48	0	-1.23	0	-0.92	0
4	-0.14	0	-0.28	0	-0.19	0
5	+1.00	0	+8.3	0	+0.56	0
6	-0.08	0	-0.55	0	-1.98	0
7	-2.12	3	-2.86	1	+0.05	0

Key to physical appearance: 0—no visible effect; 1—lost lustre; 2—lost lustre, blanched; 3—lost lustre, etched.

EXAMPLE 6

A two-inch sample of video recording tape is placed in a Soxhlet extractor; the extractor flask is filled with solvent and the solvent is heated under reflux. After 20 passes of solvent through the extractor the tape is removed, dried and examined to determine its condition. Table III gives results for a number of solvents.

Table III

Solvent:	Tape condition
Solvent A	No change.
Solvent B	No change.
Perchloroethylene	Some removal of coating at folds.
Trichloroethylene	Coating about 3% removed.
Methylchloroform	Coating about 2% removed.
Methylene chloride	Coating completely removed.
1,1,2-trichloro-1,2,2-trifluoroethane	Some removal of coating at folds.

These results show that Solvent A and Solvent B are superior to prior art solvents in their physical effect on magnetic tape.

Table IV

	Solvent	Cleaning time, sec.	Tape Condition
20	Solvent A	90	Clean, no effect on coating.
	Solvent B	90	Clean, no effect on coating.
	Perchloroethylene	30	Pinholes in coating.
	Trichloroethylene	30	About 0.4% of coating removed.
25	Methylchloroform	10	About 5% of coating removed.
	1,1,2-trichloro-1,2,2-trifluoroethane	90	Pinholes in coating.

These results show that Solvents A and B are superior to the other solvents tested in that they cause no deterioration of the tape within the time allotted for the test, and yet are completely effective in cleaning the tape during this period.

It is desirable that a solvent which is to be used for cleaning electronic parts have a high capacity for removal of flux. Therefore, several solvents are tested for their capacity to remove Kester electronic soldering flux under ultrasonic cleaning conditions.

In Test A, a thin coating of soldering flux is applied to a previously weighed and cleaned glass plate which measures about 1 1/4 x 3 inches. The plate is reweighed after the application of the flux coating and is then suspended in a test tube containing the solvent, in an ultrasonic generator identical with that used in Example 7. The plate is treated with the solvent for 5 seconds and then air-dried and weighed. In Test B, the flux-covered plate is baked for 5 minutes at 340° F. prior to cleaning. The results of these tests are summarized in Table V.

Table V

Solvent	Test A			Test B
	Percent Flux removed	Plate Appearance	Solvent appearance after 16 hours	
Solvent A	99.39	Clean	Flux in suspension	60.3
Solvent B	99.84	do	do	95.9
Perchloroethylene	99.13	White residue	Flux in solution	
Trichloroethylene	99.08	Trace residue	do	73.5
Methylchloroform	99.79	White residue	Some flux precipitated	92.4
1,1,2-trichloro-1,2,2-trifluoroethane	98.99	do	Flux precipitated	50.5

EXAMPLE 7

Further evaluation of several solvents as cleaning agents for magnetic recording tapes is carried out by placing a test tube containing the solvent in an ultrasonic generator (Hypersonic Model BU-201, manufactured by Brush Development Company). A two-inch piece of Mylar-backed video recording tape is suspended in the solvent and the frequency of the generator is adjusted to produce maximum cavitation. After the indicated treatment period, the tape is removed, dried and inspected. The results are shown in Table IV.

It will be seen from Table V that Solvents A and B are superior to all other solvents except methylchloroform for the removal of flux under normal conditions. They are superior to methylchloroform in the condition of the plates and solvent after the cleaning process. Further, Solvent B is vastly superior to all other solvents tested in removal of flux after baking.

EXAMPLE 9

This example tests several solvents for the removal of lubricants used on electronic parts such as potentiometers. Glass plates similar to those used in Example 8 are coated

with Walsco 26-01 lubricant. The plates are weighed before and after coating and are then dipped in the solvent for a period of 30 seconds. They are removed, dried and reweighed to determine the percentage of lubricant removed. The results are given in Table VI.

Table VI

Solvent:	Percent lubricant removed
Solvent A	48.8
Solvent B	57.0
Perchloroethylene	83.0
Trichloroethylene	91.9
Methylchloroform	52.8
1,1,2-trichloro-1,2,2-trifluoroethane	47.8

The results of this test show that Solvents A and B are superior to trichloroethylene and perchloroethylene in that they remove much less lubricant.

EXAMPLE 10

Resistors and similar parts used in electronic circuits usually have color codings on their surfaces to show their resistances in ohms and other properties. It is essential that solvents used for cleaning these resistors should not dissolve or obliterate the coding marks.

In this example, resistors are soaked for 5 minutes in a number of solvents and are then dried and examined for survival of the coding marks. Solvents A and B and 1,1,2-trichloro-1,2,2-trifluoroethane have no effect on the resistor color codings. In the cases of perchloroethylene, trichloroethylene and methylchloroform, the codings are obliterated by scraping after treatment with the solvent. This example shows that the solvents of this invention are superior to many of those previously known in that they do not damage the surfaces of resistors and other color-coded articles.

EXAMPLE 11

The behavior of Solvent B as a dry cleaning solvent in actual use is tested by running a number of dry cleaning loads in a Westinghouse Laundromat coin-operated dry cleaning machine. The solvent contains 1% of Perk Sheen 324 detergent (Adco, Inc.), an anionic emulsifier, and 0.07% each of epichlorohydrin and ethyl acetate as stabilizers.

The machine is operated on the following cycle.

Operation:	Time, min.
(A) Load	Variable
(B) Wash	6
(C) Drain	1
(D) Spin	4
(E) Auto dry	Variable
(F) Hot air dry	2
(G) Cool	3
(H) Purge	3

(A) As machine operation is begun, the clothes are tumbled at 51 r.p.m. as solvent enters the tub from the storage tank through a filter.

(B) When sufficient solvent is in the tub, the washing cycle begins. The solvent is continually circulated through the filter to avoid soil buildup.

(C) During the drain period, the solvent is returned (through the filter) to the storage tank.

(D) Drainage of solvent is completed by spinning the clothes at 265 r.p.m.

(E) During the auto dry period, air heated to 104-107° C. is blown over the clothes. The effluent air containing solvent vapors is cooled by passage through a water-cooled condenser at about 40° C.; the condensed solvent and water are directed to a separator from which the solvent is returned to storage and the water is dis-

carded. Air from the condenser is reheated and recycled to the tub. As the solvent content of the effluent air decreases, the air temperature rises; when it has reached 74° C., a thermostat returns the machine to the programmed cycle.

(F) Hot air continues to circulate for two minutes after the auto dry period.

(G) Unheated air is passed into the tub to cool the clothes.

(H) Finally, fresh air is drawn into the machine from the atmosphere and vented to the atmosphere in the "purge" operation.

A total of 115 cycles are run over a ten-day period. In each cycle, a load of clothes weighing approximately eight pounds is cleaned; each load contains a wide variety of fabrics and colors. The amount of dirt in the clothes varies from light to heavy; a number of "maintenance loads" containing a very high grease, oil and tar content are also run.

20 *Cleaning ability.*—A qualitative comparison of clothes cleaned with Solvent B with clothes cleaned with perchloroethylene indicates that Solvent B is at least as effective as perchloroethylene and possibly more effective. Quantitative tests, run on cloth swatches containing four 25 standard soil samples, indicate that Solvent B is, on the average, 9.08% to 10.73% more effective than perchloroethylene.

30 *Soil redeposition.*—Examination of wool and cotton swatches included in several loads during the test shows that soil redeposition is about 15.3% to 17.3% less with Solvent B than with perchloroethylene.

35 *Dye bleeding.*—No evidence of dye bleeding is noted, even after cleaning of a "red load" containing clothes of various fabrics all of which are red except for one pair of white pants. Even striped garments (e.g., red and white stripes) show no bleeding.

40 *Shrinkage.*—Shrinkage of wool garments is about 2-4%, which is comparable to that resulting from cleaning with perchloroethylene.

45 *Solvent retention.*—Qualitative comparisons indicate that clothes cleaned with Solvent B have less residual solvent odor than clothes cleaned with perchloroethylene.

Solvent acidity.—No acidic decomposition products are 45 detected in the purge air or in the water separated from the solvent during the auto dry period.

50 *Solvent recovery.*—Most of the solvent is recovered during the drain and spin operations. The remainder is removed during the auto dry process, the length of which is an indication of the condensation rate of the solvent. Recovery of Solvent B is virtually complete after thirteen minutes of drying, as compared with eighteen minutes for perchloroethylene.

55 It is to be understood that the invention is not limited by the specific examples and embodiments described hereinabove, but includes such changes and modifications as may be apparent to one skilled in the art upon reading the appended claims.

60 What is claimed is:

1. A cleaning solvent consisting essentially of a substantially constant-boiling mixture of about 70-85% by weight of at least one tetrachlorodifluoroethane and about 15-30% by weight of 1,1,2-trichloro-1-fluoroethane.

65 2. A cleaning solvent consisting essentially of about 75-80% by weight of a mixture of isomeric tetrachlorodifluoroethanes and about 20-25% by weight of 1,1,2-trichloro-1-fluoroethane.

70 3. A cleaning solvent consisting of about 75% by weight of a mixture of isomeric tetrachlorodifluoroethanes and about 25% by weight of 1,1,2-trichloro-1-fluoroethane.

75 4. A dry cleaning composition comprising the position of claim 1 in combination with up to about 2%

by weight of an emulsifying agent selected from the group consisting of anionic, cationic and nonionic types.

5. A dry cleaning composition comprising the composition of claim 2 in combination with up to about 2% by weight of an emulsifying agent selected from the group consisting of anionic, cationic and nonionic types.

6. A dry cleaning composition comprising the composition of claim 3 in combination with up to about 2% by weight of an emulsifying agent selected from the group consisting of anionic, cationic and nonionic types.
